DEVICE FOR TESTING CIGARETTES

Desmond Walter Molins, Bexley, Kent, England

Application December 14, 1932, Serial No. 647,247
In Great Britain December 14, 1931

19 Claims. (Cl. 209—79)

This invention is for improvements in or relating to cigarette making machines, and an object of the invention is to provide means whereby defective and soft ended cigarettes produced by the machine may be automatically detected and rejected or separated from the remaining cigarettes.

This object is achieved according to the present invention by providing for use with a cigarette making or packing machine, a selecting device for rejecting or separating defective (e. g. soft ended) cigarettes from the others, comprising in combination, a pair of feelers arranged to engage the opposite ends of each cigarette, at least one feeler of each pair being yieldingly mounted to move inwardly towards the other, means for delivering one cigarette at a time between said feelers, and means for releasing the cigarette from the feelers at a different time and/or place according to the movement of the yielding feeler when the particular cigarette is being tested.

It will be appreciated that the apparatus may be used for separating cigarettes of different hardness, and of different lengths within certain predetermined limits.

One construction of a cigarette selecting device made in accordance with the invention will now be described by way of example with reference to the accompanying drawings, in which:—

Fig. 1 is a side elevation of the selecting device.

Fig. 2 is an end elevation looking in the direction of the arrow 2 on Fig. 1.

Fig. 3 is an end elevation of a portion of the device looking in the opposite direction to that shown in Fig. 2, and

Fig. 4 is a perspective view showing the manner in which the cigarettes are gripped and released.

Like reference numerals refer to like parts throughout the several figures of the drawings.

The selecting device is preferably arranged at the end of a continuous rod cigarette machine.

The cigarettes 5, as they issue on the conveyor 115 from the cut-off of the machine, are deflected at right angles to their path in the machine by deflectors 6 over a tilttable plate 7 and between guides 8 and 9 to the arcuate grooves between projections 10 on discs 11 which rotate on a shaft 111 in the direction shown on the drawings.

Above the pairs of rotating discs 11 there are mounted rotatable carriers which comprise feel-

ers for the cigarettes. The feelers are arranged in pairs, one feeler of each pair being constituted by a stud 12 on a rotatable disc 13 on a shaft 113 while the other feeler of each pair is comprised by a stud 14 on a radial arm 15 which is spring urged by means of a spring 16 towards its opposite stud 12. The movable arms 15 are carried on the rotating shaft 113 and project through grooves 18 in a cylindrical flange on the disc 17. The parts are so arranged that the discs 13 and 17 lie outside the discs 11, while the axes of the shafts 111 and 113 and also that of the deflector 6 are all parallel to one another. In this way, the cigarettes are removed laterally from the conveyor 115.

The deflector blades 6 are arranged to rotate between the discs 11 and the apparatus is so timed that each deflector blade in turn coincides with succeeding grooves in the discs 11 as the deflectors revolve.

All the cigarettes delivered from the cut-off of the cigarette making machine are thereby transferred in turn to the grooves between the projections 10 and the discs 11, and they are retained in position by the circumferential guides 9 provided near the edge of the revolving discs. Lateral guides 90 are provided to ensure that the cigarettes have their ends in alignment.

Each pair of feelers 12 and 14 of the carrier are so arranged on the shaft 113 and the rotation of the latter is so arranged, that each pair of feelers moves in synchronism with the arrival of a cigarette at the detecting position.

As shown in Fig. 1, the arm 15¹ is moved past the trailing end of a cam 19 and is moved inwardly towards the opposite feeler 12 by a spring 16 and a cigarette 5¹ is thereby gripped. As the discs 13 and 17 continue to rotate still further, the arm 15¹ approaches the leading edge of a cam 20. This cam 20 lies outwardly beyond a predetermined point so as only to be in the path of any of the arms 15 that are gripping a cigarette which is of the proper length and the ends of which are of the desired degree of hardness. In this case, the arm 15¹ carrying the cigarette 5¹ which is a good one, will be pressed outwardly beyond the leading edge of the cam 20 so that as the shaft 113 and the discs 13 and 17 rotate, the arm 15¹ will engage the outer face of the cam 20 and will be moved outwardly thereby so that the cigarette 5¹ is released. As shown in Fig. 4 this release has just taken place.

The inner face of the cam 20 is, however, such that if a defective cigarette, such as cigarette 5² shown in Figs. 1 and 4, is either too short or is soft at the ends so that the feelers 12 and 14 penetrate into the cigarette, the arms 15 gripping such cigarettes, will pass the leading edge of the cam 20 on the inside, and consequently, the faulty or defective cigarettes such as the cigarette 5¹ will be carried on by the rotating discs 13 and 17. The leading edge of the cam 20 is constituted by a separate element 120 that is pivotally mounted about a pin 121 and urged into its normal position by a tension spring 122. This mounting allows the element 120 to tilt back if it is accidentally struck by one of the arms 15, so as to allow the arm to pass by without damaging the machine.

For the sake of clearness, in Fig. 4, the part 120 has not been shown separate from the cam 20. In order to allow cigarettes of different lengths to be tested, provision is made to adjust the discs 17 axially along the spindle 113. This adjustment may be effected by thumb-screw 124 shown on the right-hand side of Fig. 2. A similar adjusting device would be employed, although not shown in the drawings, for effecting the axial adjustment of the disc 17 on that side.

At the rear end of the cam 20, there is provided a catcher 21 into which the faulty or defective cigarettes are dropped. These latter are released by the feelers at the proper time by a cam 19. As seen in Fig. 3, the leading edge of the cam 19 is curved inwardly so that any feeler arms 15 which lie on the inside of the cam 20, will be gradually pressed outwardly by the cam 19 so as to release the cigarettes at the proper time into the catcher.

The other feeler arms 15 (such as the arm 15¹) which have moved along the outside of the cam 20, move against the cam 19 under the tension of the springs 16 when they have passed the trailing end of the cam 20.

Thus all the arms 15, whether they engage a good or a defective cigarette, will eventually engage the outer face of the cam 19.

The cam 19 is arranged to hold the feeler arm 15 outwardly beyond the ends of the cigarettes which are carried by the discs 11, so that as the arms 15 pass the trailing edge of the cam 19, they move inwardly under the influence of their springs 16 to engage the cigarette.

It has just been shown that the faulty cigarettes are dropped into a catcher 21, and it will be necessary to describe how the other cigarettes are removed from the selecting device.

The sequence of events will be more clearly understood from a consideration of Fig. 4 of the drawings. In this case, the arm 15¹, which only a moment ago gripped the end of the cigarette 5¹ as shown in Fig. 1, has now reached the leading edge of the cam 20 and has been pressed outwardly thereby. The cigarette 5¹ is, therefore, released almost immediately after being gripped and falls back into the same groove in the discs 11 in which it was previously carried. The tested cigarettes such as 5¹ are carried round by the discs 11 between pairs of lateral guides 22, which set their ends in proper alignment. A shield 23 prevents them from leaving the discs 11 radially and ensures that they are carried down between guides 24 and 25, the latter being constituted by a spring finger. The cigarettes are thereby allowed to fall on to

a travelling band 26, which may be the usual delivery band of the machine.

As shown in Fig. 2, two pairs of detectors are provided side by side in practice, the cigarettes being deflected to each detector alternately. A partition 28 separates the cigarettes on the delivery band 26.

In the event of the detecting apparatus ceasing to operate for any reason at all, the plate 7 can be lowered so that the cigarettes may be deflected from the conveyor 115 directly to the conveyor 26. In order, in such a case, to reduce the speed of the cigarettes, a flap 27 of flexible material (for example, of felt) is provided, supported from the guide 24.

It will be appreciated that the selecting device need not be used in conjunction with a cigarette making machine as described above, as it may be used independent of the latter for checking made cigarettes.

What I claim as my invention and desire to secure by Letters Patent is:—

1. A testing device for testing the consistency of the filling of cigarettes and separating defective cigarettes from the others, comprising in combination, a pair of studs arranged to engage and enter the opposite ends of each cigarette, one stud of each pair being yieldingly mounted to move inwardly toward the other to an extent determined by the consistency of the cigarette, means for delivering one cigarette at a time between said studs, and means for releasing the cigarettes from the studs at a different time and place dependent upon the extent of movement of the yielding stud when the particular cigarette is being tested.

2. A testing device for testing the consistency of the filling of cigarettes and separating defective cigarettes from the others, comprising in combination, a movable carrier having at least one pair of studs operative to engage and enter opposite ends of a cigarette, at least one stud of each pair being yieldingly mounted to move inwardly toward the other to an extent determined by the consistency of the cigarette, means moving in timed relationship to the carrier for feeding one cigarette at a time between the studs, and means operative to control the studs in such a manner as to release a cigarette at a different time and place when a stud has moved inwardly beyond a predetermined point than otherwise.

3. A testing device for testing the consistency of the filling of cigarettes and separating defective cigarettes from the others, comprising in combination, a plurality of pairs of feelers arranged to engage and enter the opposite ends of each cigarette, at least one feeler of each pair being yieldingly mounted to move inwardly toward the other to an extent determined by the consistency of the cigarette, means operative to receive each individual cigarette and convey it between a pair of feelers in axial alignment therewith, and means for releasing the cigarette from the feelers at a different time and place dependent upon the extent of movement of the yielding feeler when the particular cigarette is being tested.

4. A testing device for testing the consistency of the filling of cigarettes and separating defective cigarettes from the others, comprising in combination, a plurality of pairs of feelers arranged to engage and enter the opposite ends of each cigarette, at least one feeler of each pair being yieldingly mounted to move inwardly

- toward the other to an extent determined by the consistency of the cigarette, means operative to receive each individual cigarette and convey it between a pair of feelers in axial alignment therewith, said means being movable in substantially the same direction and speed at the time the cigarette is fed between the feelers, and means for releasing the cigarette from the feelers at a different time and place dependent upon the extent of movement of the yielding feeler when the particular cigarette is being tested. 5
5. A testing device for testing the consistency of the filling of cigarettes and separating defective cigarettes from the others, comprising in combination, a plurality of pairs of studs arranged to engage and enter opposite ends of each cigarette, one stud of each pair being yieldingly mounted to move inwardly toward the other to an extent determined by the consistency of the cigarette, means operative to receive each individual cigarette and convey it between a pair of studs in axial alignment therewith, and means for releasing the cigarette from the studs at a different time and place dependent upon the extent of movement of the yielding stud when the particular cigarette is being tested. 10
6. A testing device for testing the consistency of the filling of cigarettes and separating defective cigarettes from the others, comprising in combination, a plurality of pairs of studs arranged to engage and enter the opposite ends of each cigarette, one stud of each pair being yieldingly mounted to move inwardly toward the other to an extent determined by the consistency of the cigarette, means operative to receive each individual cigarette and convey it between a pair of studs in axial alignment therewith, said means being movable in substantially the same direction and speed at the time the cigarette is being fed between the studs, and means for releasing the cigarette from the feelers at a different time and place dependent upon the extent of movement of the yielding stud when the particular cigarette is being tested. 15
7. A testing device for testing the consistency of the filling of cigarettes and separating defective cigarettes from the others, comprising in combination, a movable carrier having at least one pair of feelers operative to engage and enter opposite ends of a cigarette, at least one feeler of each pair being yieldingly mounted to move inwardly toward the other to an extent determined by the consistency of the cigarette, means operative to receive each individual cigarette and convey it between a pair of feelers in axial alignment therewith, and means operative to control the feelers in such a manner as to release a cigarette at a different time and place, when a feeler has moved inwardly beyond a predetermined point than otherwise. 20
8. A testing device for testing the consistency of the filling of cigarettes and separating defective cigarettes from the others, comprising in combination, a movable carrier having at least one pair of feelers for opposite ends of a cigarette, at least one feeler of each pair being resiliently mounted and arranged to move inwardly toward the other and enter the cigarette to an extent determined by the consistency of the cigarette, and a device rotatable with respect to and between opposed feelers for delivering cigarettes to the latter. 25
9. A testing device for testing the consistency of the filling of cigarettes and separating defective cigarettes from the others, comprising in combination, a movable carrier having at least one pair of studs for opposite ends of a cigarette, at least one stud of each pair being resiliently mounted and arranged to move inwardly toward the other to an extent determined by the consistency of the cigarette, a pair of discs rotatable between opposed studs for delivering cigarettes to the latter, said discs being provided with means operative to control the cigarettes, and a rotatable deflector between the said discs, said deflector having its axis of rotation parallel to that of the discs and of the axes of the cigarettes. 30
10. A testing device for testing the consistency of the filling of cigarettes and separating defective cigarettes from the others, comprising in combination, a movable carrier having at least one pair of feelers operative to engage and enter opposite ends of a cigarette, at least one feeler of each pair being yieldingly mounted to move inwardly toward the other to an extent determined by the consistency of the cigarette, means operative in timed relationship to the carrier to feed one cigarette at a time between the feelers, a cam situated in the path of the movable feelers and operative to control those feelers which are pressed sufficiently far outwardly by the cigarettes held between them, said cam being clear of the feelers when they engage defective cigarettes, and a second cam situated behind the last mentioned cam and operative in the path of the feelers engaging defective cigarettes to release the latter. 35
11. A testing device for testing the consistency of the filling of cigarettes and separating defective cigarettes from the others, comprising in combination, a pair of feelers arranged to engage the opposite ends of each cigarette, one feeler of each pair being yieldingly mounted to move inwardly toward the other to an extent determined by the consistency of the cigarette, a pair of discs rotatable between opposed feelers for delivering cigarettes to the latter, a deflector rotatable between the said discs about an axis parallel to that of the discs and of the cigarettes, a cam situated in the path of the movable feelers and operative to control those feelers which are pressed sufficiently far outwardly by the cigarettes held between them, said cam being clear of the feelers when they engage defective cigarettes, and a second cam situated behind the last mentioned cam and operative in the path of the feelers engaging defective cigarettes to release the same. 40
12. A testing device for testing the consistency of the filling of cigarettes and separating defective cigarettes from the others, comprising in combination, a movable carrier having at least one pair of feelers operative to engage opposite ends of a cigarette, at least one feeler of each pair being resiliently mounted and arranged to move inwardly toward the other to an extent determined by the consistency of the cigarette, a pair of discs rotatable between opposed feelers for delivering cigarettes to the latter, a deflector rotatable between the said discs and about an axis parallel to that of the discs and of the cigarettes, a cam situated in the path of the movable feelers and operative to control those feelers which are pressed sufficiently far outwardly by the cigarettes held between them, said cam being clear of the feelers when they engage defective cigarettes, and a second cam situated behind the last mentioned cam, and operative in the path of the feelers engaging defective cigarettes to release the same. 45

- of the feelers engaging defective cigarettes, to release the defective cigarettes.
13. A testing device for testing the consistency of the filling of cigarettes and separating defective cigarettes from the others, comprising in combination a rotatable shaft having mounted thereon a movable carrier composed of two parts, one of which is fixed to the shaft and the other adjustably mounted thereon, radial arms resiliently mounted on the adjustable part and provided with studs, said fixed part being provided with studs directed toward and in alignment with said first named studs, the two parts of the carrier being spaced apart upon the shaft and each pair of aligned studs being operative to engage and enter the ends of a cigarette.
14. A testing device for testing the consistency of the filling of cigarettes and separating defective cigarettes from the others, comprising in combination a rotatable shaft having mounted thereon a movable carrier composed of two parts, one of which is fixed to the shaft and the other adjustably mounted thereon, radial arms resiliently mounted on the adjustable part and provided with studs, said fixed part being provided with studs directed toward and in alignment with said first named studs, the two parts of the carrier being spaced apart upon the shaft and each pair of aligned studs being operative to engage and enter the ends of a cigarette, a cam situated in the path of the radial arms and operative to control those arms which are pressed sufficiently far outwardly by the cigarettes held between them and the fixed studs, said cam being clear of the radial arms when they engage defective cigarettes, and a second cam situated rearwardly of the last mentioned cam and operative in the path of the arms, the studs of which engage defective cigarettes, to release the same.
15. A testing device for testing the consistency of the filling of cigarettes and separating defective cigarettes from the others, comprising in combination a rotatable shaft having mounted thereon a movable carrier composed of two parts, one of which is fixed to the shaft and the other adjustably mounted thereon, radial arms resiliently mounted on the adjustable part and provided with studs, said fixed part being provided with studs directed toward and in alignment with said first named studs, the two parts of the carrier being spaced apart upon the shaft and each pair of aligned studs being operative to engage and enter the ends of a cigarette, a cam situated in the path of the radial arms and operative to control those arms which are pressed sufficiently far outwardly by the cigarettes held between them and the fixed studs, said cam being clear of the radial arms when they engage defective cigarettes, and a second cam situated rearwardly of the last mentioned cam and operative in the path of the arms, the studs of which engage defective cigarettes, to release the same.
16. A testing device for testing the consistency of the filling of cigarettes and separating defective cigarettes from the others, comprising in combination a rotatable shaft having mounted thereon a movable carrier composed of two parts, one of which is fixed to the shaft and the other adjustably mounted thereon, radial arms resiliently mounted on the adjustable part and provided with studs, said fixed part being provided with studs directed toward and in alignment with said first named studs, the two parts of the carrier being spaced apart upon the shaft and each pair of aligned studs being operative to engage and enter the ends of a cigarette, a cam situated in the path of the radial arms and operative to control those arms which are pressed sufficiently far outwardly by the cigarettes held between them and the fixed studs, said cam being clear of the radial arms when they engage defective cigarettes, a pivotally mounted and spring-urged element on the leading end of said cam to engage with and guide the radial arms, and a second cam situated rearwardly of the last mentioned cam and operative in the path of the arms, the studs of which engage defective cigarettes, to release the same.
17. A testing device for testing the consistency of the filling of cigarettes and separating defective cigarettes from the others, comprising in combination a rotatable shaft having mounted thereon a movable carrier composed of two parts, one of which is fixed to the shaft and the other adjustably mounted thereon, radial arms resiliently mounted on the adjustable part and provided with studs, said fixed part being provided with studs directed toward and in alignment with said first named studs, the two parts being spaced apart upon the shaft and each pair of aligned studs being operative to engage and enter the ends of a cigarette, a pair of rotatable discs disposed below and between the parts of the said movable carrier, said discs having peripheral projections, said projections being in alignment with each other and operative to receive a cigarette and feed it into position to be received by a pair of cooperating studs, a cam situated in the path of the radial arms and operative to control those arms which are pressed sufficiently far outwardly by the cigarettes held between them and the fixed studs, said cam being clear of the radial arms when they engage defective cigarettes, and a second cam situated rearwardly of the last mentioned cam and operative in the path of the arms, the studs of which engage defective cigarettes, to release the same.
18. A testing device for testing the consistency of the filling of cigarettes and separating defective cigarettes from the others, comprising in combination a rotatable shaft having mounted thereon a movable carrier composed of two parts, one of which is fixed to the shaft and the other adjustably mounted thereon, radial arms resiliently mounted on the adjustable part and provided with studs, said fixed part being provided with studs which are directed toward and in alignment with said first named studs, said parts being spaced apart upon the shaft and each pair of aligned studs being operative to engage and enter the ends of a cigarette, and an element operative to adjust said adjustable part axially upon the rotatable shaft.
19. A testing device for testing the consistency of the filling of cigarettes and separating defective cigarettes from the others, comprising in combination a rotatable shaft having mounted thereon a movable carrier composed of two parts, one of which is fixed to the shaft and the other adjustably mounted thereon, radial arms resiliently mounted on the adjustable part

and provided with studs, said fixed part being provided with studs directed toward and in alignment with said first named studs, the two parts being spaced apart upon the shaft and each pair of aligned studs being operative to engage and enter the ends of a cigarette, an element operative to adjust said adjustable part axially upon the rotatable shaft, a pair of rotatable discs disposed below and between the parts of the said movable carrier, said discs having peripheral projections, said projections being in alignment with each other and operative to receive a cigarette and feed it into position to be received by a pair of cooperating studs, a cam situated in the path of the radial arms and operative to control those arms which are pressed sufficiently far outwardly by the cigarettes held between them and the fixed studs, said cam being clear of the radial arms when they engage defective cigarettes, a pivotally mounted and spring-urged element at the leading end of said cam, and a second cam situated behind the last mentioned cam and operative in the path of the arms, the studs of which engage the defective cigarettes, to release the same. 80
